UNITED STATES PATENT OFFICE.

SAMUEL C. JONES, OF MARYVILLE, MISSOURI.

DESIGN FOR A HORSESHOE-CALK.

SPECIFICATION forming part of Design No. 27,429, dated July 27, 1897.

Application filed April 26, 1897. Serial No. 634,044. Term of patent 7 years.

To all whom it may concern:

Be it known that I, SAMUEL C. JONES, a citizen of the United States, residing at Maryville, in the county of Nodaway and State of Missouri, have invented and produced a new and original Design for Horseshoe-Calks; and I do hereby declare the following to be a full, clear, and exact description of the same, reference being had to the accompanying drawing, forming a part thereof.

My invention relates to a design for a horseshoe-calk, and is illustrated in the accompanying drawing, in which the figure shown represents a perspective view of my design.

The leading or essential features of my design consist of the calk 1, having the upper and lower parallel plates 2 3 formed with the orifices 4 and bolt 5, said plates being con-

nected at one end of the yoke 6. The bar 7 extends transversely of the said parallel plates and parallel with the yoke 6 and has its sides converging to a V-point from its upper rectangular end to its lower end, as shown.

The several portions of the calk may be engraved, chased, or otherwise ornamented, as desired.

Having thus described my invention, I claim—

The design for a horseshoe-calk, substantially as herein shown and described.

In testimony whereof I affix my signature in presence of two witnesses.

SAMUEL C. JONES.
